Attorney.

UNITED STATES PATENT OFFICE

2,021,806

CLOSURE FASTENER

Ewald F. Pawsat, Maysville, Ky., assignor to Wald Manufacturing Company, Incorporated, a corporation of Kentucky

Application November 11, 1933, Serial No. 697,646

1 Claim. (Cl. 292—162)

The present invention relates to molds for smoking, cooking or otherwise processing sausages and other meats.

The principal object of the present invention is to provide a suitable closure fastener for a mold of the type mentioned. During the smoking or other processing of sausage and similar meats, in molds, a considerable pressure is applied to the closure of the mold, and it is found that unless some positive interlocking elements of sufficient rigidity are provided, the mold will frequently spring open resulting in the loss of its contents. At the same time the closure fastener must be of extremely simple construction, and capable of rapid and certain operation in order to provide for the economical and effective accomplishment of the results desired. The present invention attains these objects by means of a closure fastener positive in operation and at the same time extremely simple and inexpensive of construction as well as operation.

In the drawing:

Figure 1 is a perspective of a mold having a closure constructed in accordance with this invention.

Figure 2 is an enlarged perspective of a portion of the interlocking elements of the closure.

Figure 3 is an end view of a mold provided with a closure in accordance with this invention.

The mold consists of two right-angular sections 1 and 2 hingedly secured together at 3. The sections 1 and 2 are constructed in the usual manner of right-angularly bent cross wires 4, and of intersecting longitudinal wires 5 in accordance with the usual construction of molds of this type. Alternate wires 4 of the section 2 are bent to form hooks 6 which when the sections are in closed position as shown in the drawing, engage over the edge longitudinal wire 7 of the section 1, said wire 7 being preferably unitary with the top and bottom wires 4 of said section 1. The hooks 6 provide a slight frictional engagement with wire 7 and thus serve as a preliminary or temporary locking means. Before the cooking or processing commences, however, the sections are interlocked by means of the mechanism next to be described.

Beyond the hooks 6 the alternate wires 4 of section 2 extend outwardly to form securing projections or standards 8 for a cross rod 9 which is secured to the free ends of the standards 8 by welding or other suitable means. Secured to the section 2 are four wires or rods 10 which terminate in loops or eyes 11. Mounted so as to slide in the eyes 11 is a lock rod 12, one end of 55 which is bent at right angles to the main section

of the rod and terminates in a loop or eye 13 which engages slidably around the rod 9. Secured by welding or other suitable means to the section 1 are wires forming rigid hooks 14. The hooks 14 are so positioned with respect to the rod 12 slidably carried by section 2 that when the sections are in closed position, said hooks engage said rod 12 so as to provide a positive interlock between the sections. In order to permit the relative movement of the sections this interlock 10 may be released by reason of the offsets or bends 15 formed in the rod 12, said bends being positioned in alignment with the hooks when desired by the slidable operation of said rod. In Figure 1 the rod 12 and hooks 14 are in relative position 15 to provide a positive interlocking closure for the sections. In Figure 2 the rod 12 having been moved to the right has brought the bends 15 into alignment with hooks 14; the hooks are therefore permitted to pass the rod thus allowing 20 the opening of the sections. The rod 12 is provided with a right angled terminal extension 16 which serves as an operating handle for the sliding of the rod in either direction, a loop 17 in the shank of said handle providing clearance for 25 the end standard 8.

From the foregoing description, it is thought that the nature and operation of the present mold closure will be apparent to those familiar with the art.

When it is desired to move the sections 1 and 2 relative to each other, the rod 12 is slid into the position shown in Figure 2. In this movement the rod operates through the eyes 11 and by its own eye or loop 13 traveling on the bar 9. In 35 this position the hooks 14 may freely pass the lock bar 12, and the sections 1 and 2 may be operated to open or close the sections. When the contents have been provided in the mold, the sections are brought to closed position, in which 40 position they may be temporarily held by the frictional engagement of the hooks 6 over the wires 7. Positive and permanent closure for 45 processing is then provided by sliding the lock rod 12 to the left, which brings the straight portions of the rod into engagement behind the hooks 14. When thus interlocked, the sections are enabled to stand pressure limited only by the strength of the materials of which the several parts are made.

Having thus fully described my invention, what I claim as new and desire to secure by Letters Patent is:

A closure fastener for hinged sections comprising a series of eyes near the edge of one of 55

said sections, a rod fixedly secured along the edge of said section beyond said eyes, a lock rod slidably mounted in said eyes, an angular extension at one end of said lock rod, an eye at the end of 5 said extension in slidable engagement around said fixed rod, an angular handle extension at the other end of said lock rod, said handle extension having a loop adapted to engage slidably the

end edge of said section to cooperate with the extension and eye at the opposite end of said lock rod, said lock rod having a series of bends to provide clearances for a series of keepers at one position of longitudinal adjustment of said lock rod, and straight portions adapted to slide behind said keepers to secure the sections together. 5
